PIETER DANIEL VAN ESSEN, OF HAAG, NETHERLANDS, ASSIGNOR TO BETHLEHEM STEEL COMPANY, A CORPORATION OF PENNSYLVANIA.

SAFETY HIGH-EXPLOSIVE IMPACT FUSE.

Application filed May 15, 1924. Serial No. 713,514.

My invention relates to impact fuses for projectiles designed to be fired from ordnance and has for an object a construction whereby the fuse is rendered safe from premature detonation in storage, in handling or during transportation, during its travel in the bore of the gun and for such time thereafter as may be determined by the requirements of firing.

10 In the drawing attached to this specification, I show in—

Fig. 1 a section of the fuse, when completely assembled, with the component parts in their inoperative position, as they exist before firing from the gun.

In Fig. 2 I show a detail in perspective of two essential components of the fuse.

In Fig. 1, I show a hollow nose fuse body 10 of suitable profile, having forwardly a threaded portion for attachment to a fuse cap 11 and having rearwardly a threaded portion for securing the fuse body to a projectile. The fuse body and the fuse cap are designed to provide a forward chamber 12 for containing the functional parts of the fuse and the fuse body is also designed to provide a rearward chamber 13 for containing the booster charge. The chambers 12 and 13 are closed rearwardly by screwed closing plugs 14 and 15, respectively. The fuse cap 11 is, in addition, bored to accommodate the striking element 17 of the detonator mechanism and to provide a first or forward shoulder 8, a second shoulder 9, and an annular recess 16, 25 for purposes to be hereinafter described. A striker 17, which for reasons of lightness I preferably make of hollow construction, carries rearwardly a needle portion 18 consisting of a flat base and a needle point in one 30 piece; said needle portion being held in position by an annular constriction or groove 19 immediately forward of it.

I also show a complete detonator 20, consisting of a holder 21 centrally bored with an axial channel 22, a screwed cap 23 adapted to hold a priming cap 25, and a detonator casing 24, containing a reinforced main detonator 28 and attached rearwardly of the holder 21. The screwed cap 23 is externally tapered 45 forwardly at 26 for a portion of its length and has a hole 27 drilled in its forward end to admit entry of the striker needle 18. The holder 21 when assembled in the fuse projects rearwardly through the closing plug 14 50 into the rear chamber 13, so that the main det-

onator 28 occupies a position in the center of the booster charge.

The two functional components of the detonating or firing mechanism, viz, the striker 17 and the detonator 20 are kept apart from each other by a safety member, viz, the spacing cage 30. This cage 30, which I show in greater detail in Fig. 2, consists of a hollow cylindrical casing having at its forward end 60 spring clutch wings 31, conforming to the annular groove 19 of the striker 17, and having their ends turned back outwardly so as to project beyond the diameter of the casing, and form hook shaped sections, susceptible of being compressed so as to closely fit the 65 wall 29 of the fuse cap. In addition, the cage 30 has four rearwardly projecting prongs 32, terminating in outwardly projecting toe pieces 33, while at a point slightly in advance of the prongs 32 an internal shoulder 34 is 70 provided. Associated with the cage 30, I also show a four winged stirrup 35 having a central hole drilled therein, and placed so that the prongs 32 straddle the four wings 36 of the stirrup 35 and the shoulder 34 rests on 75 the forward face of said stirrup. The forward end of detonator screwed cap 23 likewise supports the stirrup 35.

An inertia sleeve 37 loosely surrounds the cage 30 and is adapted to jam onto the externally tapered shoulder 26 of the screwed cap 23, when forcibly driven rearwardly thereon. The wall of the inertia sleeve is of such thickness as to be expanded when forced over the tapered shoulder 26. In this manner, 85 there are provided means for permanently clutching the inertia sleeve 37 to the screwed cap 23, upon shock of gun discharge. A reaction spring 38 shouldering on the closing plug 14, bears forwardly against the shoulder of the inertia sleeve 37.

In the assembled fuse, the clutch wings 31 of the cage 30 securely grip the striker 17 at its annular groove 19, being retained and slightly compressed therein by the constraint 90 of the fuse cap wall 29, thereby preventing any movement of the striker in relation to the cage 30 and the detonator 20. The inertia sleeve 37 shouldering forwardly on the fuse cap 11 which is securely screwed to the fuse body 10, and shouldering rearwardly on the projecting toe pieces 33 of the cage 30, effectively prevents any forward movement of the striker 17. Similarly any forward movement 95 of the detonator 20 is prevented by the wings 110

36 of the stirrup 35 which also project in rear of the inertia sleeve 37, and by the shoulder 34 of the cage 30. These members, viz, toe pieces 33 and wings 36, therefore act as abutment members, preventing any undesired forward movement of the detonator 20 and the striker 17, until the rearward movement of the inertia sleeve 37, under shock of gun discharge, has distorted them from their position of abutment.

As shown in Figure 2, the toe pieces 33 of cage 30 are substantially weaker and therefore more easily distorted by the set-back of the sleeve 37, than are the wings 31 of the cage.

The latter, due to their greater width and to the fact that, they are curved outwardly and downwardly at their extremities in hook formation, are not susceptible to distortion upon shock of discharge. The possibility of their distortion is further guarded against by the fact that, the wings 31 are compressed in a radially inward direction, owing to their confinement by the wall 29 of the fuse cap, as long as the firing mechanism is in its safe or inoperative position; that is to say, until they have been moved to a position opposite the groove 16. It is also evident that no rearward movement of the detonator mechanism is possible owing to the shouldering of the head of the striker 17 in its recess in the fuse cap 11 and the shouldering of the screwed cap 23 on the closing plug 14.

The rearward chamber 13 is adapted to contain a booster charge 40, which may consist of compressed pellets of trinitrotoluol, trinitrophenylmethylnitramine, tetranitroaniline, or of any similar aromatic nitro compound, or other explosive suitable for the purpose. The booster charge 40 may be inserted so as to leave a space 41 in a zone immediately surrounding the main detonator 28 when the latter is in its inoperative position, but which will not be contiguous to the main detonator when the latter is in its firing position. This space may be filled with some wax-like, yieldable material, such as for example, paraffin wax, cerasin wax, bitumen, etc., susceptible of effectively checking or damping the propagation of the wave of detonation, communicated by the main detonator 28 when in close juxtaposition thereto, in a manner disclosed in my U. S. Patent #1,570,983, application for which was filed May 15, 1924. The booster charge 40, together with the wax-like material filling the space 41, is kept out of contact with the rearward protruding end of the detonator casing 24 by a suitable metal lining or casing 42 having a flange 43 at its forward end, fixedly secured between the closing plug 14 and the clamping nut 44. The rear chamber is completely closed by the thin closing plug 15.

The action of the fuse on shock of gun discharge is as follows: The inertia sleeve 37 sets back, rearwardly distorting the toe pieces

33 of the cage 30 and the wings 36 of the stirrup 35, also compressing the reaction spring 38 until said inertia sleeve 37 bears firmly upon and jams on the externally tapered portion 26 of the screwed cap 23, thus becoming rigidly attached or clutched thereto. The striker 17, the cage 30, the stirrup 35 and detonator 20 being no longer restrained by the inertia sleeve 37, are, therefore, free to move forwardly.

As soon as the projectile and fuse have left the muzzle of the gun, that is to say, as soon as their acceleration has ceased, the reaction spring 38 tends to move the entire detonating mechanism forwardly, viz, the striker 17, the cage 30, the stirrup 35 and the detonator 20; but said forward movement is opposed by the air pressure due to the velocity of the projectile in flight. Owing to the continually decreasing air pressure, as the projectile passes along its trajectory, the reaction spring 38 will eventually project forwardly the entire detonating mechanism, until said forward movement is arrested by the shouldering of the detonator holder 21 on the closing plug 14. The exact point in the trajectory at which this forward movement is entirely effected can be controlled by the tension of the reaction spring 38.

In this forward position, the clutch springs 31 and the annular groove 19 are in juxtaposition to the annular recess 16 in the fuse cap 11. Said clutch springs 31 are, therefore, free to be expanded outwardly into the recess 16 in the event of the striker being driven rearwardly towards the priming cap 25. Also, in this forward or firing position the main detonator 28 is withdrawn from the protective sheath 41 in the booster charge 40, and therefore, being in juxtaposition with the unprotected portion of the booster charge, can readily communicate to it a wave of detonation, initiated by the influence of the priming cap 25, when fired by the striker needle 18.

On impact with the objective the striker 17 is retarded. Owing to the inertia of the detonator mechanism, viz, the detonator 20, stirrup 35 and cage 30, relative movement between the striker 17 and said mechanism is effected, thereby causing the clutch springs 31 to expand outwardly into the annular recess 16 and the needle point 18 and the priming cap to be brought into violent contact. The resulting flash from said priming cap 25 passes rearwardly to the main detonator 28 by the channel 22 and initiates the detonation thereof. Owing to its position, withdrawn from the protection of the wax-like material in the space 41, the wave of detonation is readily propagated to the booster charge 40 and from thence to the main explosive charge in the projectile.

From the foregoing description it will be clearly understood that the fuse I have in-

vented is particularly safe from the danger of premature detonation.

In the first place, my method of interposing a safety spacing element of special construction between the striker and the priming cap, firmly clutched to the striker at all times, except when in the firing position, makes it impossible to obtain contact between the striker and the detonator until the 10 elements comprising the detonating mechanism have been brought to the firing position. The omission of this spacing element, due to careless assembling, does not, however, render the fuse dangerous, as long as the detonator 15 itself is retained in its inoperative position; besides which, the inversion of the fuse during handling would, in the absence of the safety distance piece, cause the striker to drop out of the fuse altogether. The detonator mechanism is secured in an inoperative 20 position, by an inertia sleeve, from the restraining effect of which it is only released after the shock of gun discharge. Accidental dropping of the fused projectile prior to firing 25 will not effect this release. Even after such release has been effected on "set back", the fuse is still inoperative in the bore of the gun, owing to the acceleration of the projectile therein, and further its movement to 30 an operative position can be delayed to any desired point in its trajectory. Finally, even if, through some unforeseen cause, the detonator were fired, during storage, during handling, or while in the gun, its position in 35 regard to the booster charge and its protective sheath is such that the detonation of the latter would not be effected.

Having thus fully described my invention, what I claim is:

1. In a fuse for a projectile, the combination of a firing pin, a detonator member, a spacing member interposed between the firing pin and the detonator member so that forward movement of the latter will move the firing pin to its forward position through the medium of the spacing member, and means for normally preventing forward movement of the spacing member and rendered ineffective upon discharge of the projectile from a gun.

2. In a fuse for a projectile, the combination of a firing pin, a detonator member, a spacing member interposed between the firing pin and the detonator member so that forward movement of the latter will move the firing pin to its forward position through the medium of the spacing member, an inertia member, and means cooperating with the latter member for normally preventing forward movement of the spacing member and rendered ineffective upon discharge of a projectile from a gun.

3. In a fuse for a projectile, the combination of a firing pin, a detonator member, a spacing member inter-connecting the firing

pin and the detonator member so that forward movement of the latter will move the firing pin to its forward position, an inertia member, means cooperating with the latter member for normally preventing forward movement of the spacing member and rendered ineffective upon discharge of a projectile from a gun, and a spring compressed by said inertia member and effective to move the connected parts forwardly.

4. In a fuse for a projectile, the combination of a striking member having a depression, a detonating member, and a safety member fitting against one end of the detonating member and having spring tongue means to engage in the depression of the striking member, said safety member being rendered ineffective by the unitary movement of the striking and detonating members to a firing position.

5. A projectile fuse comprising striking and detonating members movable from inoperative to firing positions, a safety member for separating the striking and detonating members, clutching means for connecting the safety member to one of the first-named members as long as the latter occupy inoperative positions and releasable when such members move forwardly to a predetermined extent, and means for normally holding the detonating member in inoperative position.

6. In a fuse, the combination of a body having a cavity provided with an internal shoulder, striking and detonating members in the cavity, a safety member interposed between the striking and detonating members, a releasable connection between the safety member and the striking member, an inertia member surrounding the safety member, a spring for holding the inertia member in contact with said shoulder, deformable means carried by the safety member and extending outwardly of the interior of the inertia member for preventing its forward movement in respect to the latter and adapted to be deformed upon rearward movement of the inertia member, and means for clutching the inertia member to the detonating member when said rearward movement has been effected.

7. In a fuse, the combination of a striking member having an annular groove therein, a detonating member, a safety member for spacing the striking member from the detonating member, said safety member having spring tongues for engagement in the annular groove of the striking member, an inertia member surrounding the safety member, means on the safety member for preventing its forward movement in respect to the inertia member and adapted to be deformed upon rearward movement of the latter, and means for clutching the detonating member to the inertia member when said rearward movement has been effected.

8. In a fuse, the combination of a striking member including a hollow shell carrying a firing pin, said shell having a depression therein, a detonating member, a spacing member, said lugs adapted to be deformed upon rearward movement of the inertia member, and means for clutching the detonator member to the inertia member when said rearward movement has been effected. 70
- 5 member engaging the detonating member and having spring tongue means for engagement in the depression of the striking member, an inertia member for preventing its forward movement in respect to the inertia member, 75
- 10 means carried by the spacing member and deformed by the inertia member upon its rearward movement and means for connecting the detonating member to the inertia member when said rearward movement has 80
- 15 been effected. 85
9. In a fuse, the combination of a body portion having an axial chamber open at the nose end of the body, said chamber having first and second shoulders and a depression adjacent to the first shoulder, an impact member of shell construction in the chamber and having a head portion for engagement with the first shoulder to limit rearward movement of the impact member, a firing pin carried by 90
- 20 the impact member, said impact member having a depression adjacent to the firing pin, a detonator member, means for spacing the detonator member from the impact member, said spacing means including spring means adapted to be engaged in the depression of the impact member and to be confined in engaged position by a portion of the wall of the chamber until such spring tongue means come opposite to the depression adjacent to the first 95
- 25 shoulder, a spring for maintaining the inertia member in contact with the second shoulder, means carried by the spacing member for preventing forward movement of the latter in respect to the inertia member and adapted to be deformed by said inertia member upon 100
- 30 its rearward movement and means for connecting the detonator member to the inertia member when said rearward movement has been effected. 105
- 40
- 45 10. In a fuse, the combination of a body portion having an axial chamber open to the nose end, said chamber having an internal annular rib and an annular groove at the rear side of the rib, a hollow impact member having a head portion adapted to contact with the rib to limit rearward movement of the impact member, a firing pin carried by the inner end of the impact member, said impact member having an annular groove there- 110
- 50 in, a detonator member, a spacing member for spacing the detonator and impact members, said spacing member having spring tongues adapted to engage in the annular groove of the impact member and to be confined in engaged position by the chamber wall until such tongues come opposite to the annular groove adjoining the rib, an inertia member surrounding the spacing member, deformable lugs carried by the latter and ex- 115
- 55 tending outwardly of the bore of the inertia 120
- 60
- 65
13. In a fuse, the combination of a body portion having an axial passage open at the nose end and provided with first and second shoulders and an annular groove adjacent to the first shoulder, an impact member in the chamber and having a shoulder adjacent to its forward end to limit rearward movement thereof, a firing pin carried by the rear end of the impact member, said impact member having an annular groove adjacent to its rear end, a detonator member in the chamber 125
- 130

- and disposed rearwardly of the firing pin, means for limiting rearward movement of the detonator member, a spacing device having an abutment portion bearing against the forward end of the detonator member and having spring means held engaged in the groove of the impact member by the chamber wall until the spring means come opposite to the chamber groove, an inertia spacing device surrounding the spacing device, a spring in the chamber for biasing the inertia member toward the second shoulder, tongues carried by the sleeve and projecting outwardly of the rear end of the inertia member to limit forward movement of the connected impact member and spacing device with respect to the inertia member, said tongues being deformable upon movement of the inertia member relative to the spacing device, and clutch portions carried by the inertia and detonator members for connecting them together upon rearward movement of the inertia member to a suitable extent.
14. In a fuse for a projectile, the combination of a fuse body, a detonator member, a firing pin slidably mounted in said body, a member temporarily interposed between the firing pin and the detonator member so that both members may be moved in unison to active position, means normally preventing said movement but rendered ineffective at the discharge of the projectile from a gun, and means operable after the last named means is rendered ineffective to move the firing pin and detonator member into active position.
15. In a fuse for a projectile, the combination of a fuse body, a firing pin slidably mounted in the fuse body, a detonator slidably mounted in the fuse body, a member temporarily interposed between the firing pin and the detonator member so that both members may be moved in unison to active position, means including an inertia member for normally preventing said movement but rendered ineffective at the discharge of the projectile from a gun, and means to store energy induced by said inertia member for moving the firing pin and detonator member into active position.
16. In a fuse for a projectile, the combination of a fuse body, a firing pin slidably mounted in the fuse body, a detonator member slidably mounted in the fuse body, a member temporarily interposed between the firing pin and the detonator member so that both members may be moved in unison to active position, an inertia member, an abutment member engaging the latter member for normally preventing said movement but rendered ineffective by the movement of said inertia member at the discharge of the projectile from a gun, and means to store energy induced by the inertia member for moving the firing pin and detonator member into active position, said movement of said inertia mem-
- ber operatively connecting it to the detonator member whereby the latter and the firing pin may be moved to their active position.
17. In a fuse for a projectile the combination of a fuse body having an open recess formed therein, a direct impact striker mounted in said recess, a shoulder formed on said striker, a detonator member, and a safety member engaging one end of the detonator member and having spring tongue means to engage said shoulder.
18. In a fuse, the combination of a striking member having a shoulder formed thereon, a detonator member, a safety member for spacing the striking member from the detonator member, said safety member having spring tongues for engaging said shoulder, an inertia member, means cooperating with the latter for normally preventing the forward movement of the detonator member, and means for clutching the latter member to the inertia member upon rearward movement of the latter.
19. In a fuse, the combination of a fuse body having a cavity therein, a striker mounted in said cavity, a detonator member mounted in said cavity, a safety member interposed between the striker and the detonator member, a releasable connection between said safety member and the striker, an inertia member, means cooperating with the latter member to prevent the forward movement of the detonator member and rendered ineffective during the rearward movement of the inertia member, a spring compressed by the latter during said movement and effective to move the detonator member forwardly, and means for locking said releasable connection during the initial flight of the projectile.
20. In a fuse, the combination of a fuse body having an open cavity, a striker mounted in said cavity, a detonator member, a safety member interposed between the latter and the striker, a releasable connection between said safety member and the striker, means to store and impart energy induced by the acceleration of the projectile to effect the forward movement of the striker, and means to lock said releasable connection during the forward movement of said striker.
21. In a fuse for projectiles, the combination of a direct impact striker, a detonator member, a safety member interposed between the latter and said striker so that forward movement of the detonator member will move the striker member to active position, means to normally prevent the forward movement of the detonator member and rendered ineffective at the discharge of the projectile from a gun, and means energized by said discharge effective to move said detonator member forwardly, whereby the striker member is moved forwardly to its active position.
22. In a fuse for a projectile, the combi-

nation of a striker member of the direct impact type and having a shoulder formed thereon, a detonator member, a safety member engaging one end of the detonator member and having spring tongue means to engage said shoulder, and means for normally preventing the forward movement of said detonator member and rendered ineffective at discharge of the projectile from a gun.

23. In a fuse for a projectile, the combination of a striker member of the direct impact type and having a shoulder formed thereon, a detonator member, a safety member engaging one end of the detonator member and having spring tongue means to engage said shoulder, means for normally preventing the forward movement of said detonator member and rendered ineffective at discharge of the projectile from a gun, and means energized by said discharge effective to move said detonator forwardly and the striker member to its active position.

24. In a fuse for a projectile, the combination of a striker member of the direct impact type and having a shoulder formed thereon, a detonator member, a safety member engaging one end of the detonator member and having spring tongue means to engage said shoulder, an inertia member surrounding said detonator member, a member having lateral projections cooperating with said inertia member to normally prevent the forward movement of said detonator member, and a spring compressed by the rearward movement of said inertia member, said movement of the latter member operatively connecting it to the detonator member.

25. In a fuse for a projectile, the combination of a striker member of the direct impact type and having a shoulder formed thereon, a detonator member, a safety member engaging one end of the detonator member and having spring tongue means to engage said shoulder, an inertia member surrounding said detonator member, a member having lateral projections cooperating with said inertia member to normally prevent the forward movement of said detonator member, a spring compressed by the rearward movement of said inertia member, and means for clutching the latter member to the detonating member upon rearward movement of the inertia member.

26. In a fuse for a projectile, the combination of a fuse body having a recess formed therein, a striker mounted in said recess, a detonator member, and a safety member adapted to yieldingly prevent the movement of the striker and detonator towards each other, the walls of said recess normally engaging said safety member to positively prevent said movement.

27. In a fuse for projectiles, the combination of a striker, a detonator member, a safety member adapted to yieldingly pre-

vent the movement of the striker and detonator member towards each other during the flight of the projectile, and means to transmit a component of the impact forces in a radial direction to render said safety member ineffective.

28. In a fuse for projectiles, the combination of a striker member, a detonator member, and a safety means interposed between the striker member and the detonator member and adapted to yieldingly engage one of said members at its periphery to constrain said members apart during the flight of the projectile, said members being disposed in the fuse so that their mutual approach may be effected by the direct forces of impact.

29. In a fuse for projectiles of the supersensitive type, the combination of a striker member of the direct impact type, a detonator member, and restraining means interposed between said members to yieldingly hold them apart during the flight of the projectile and of sufficient strength to oppose the forces applied to the parts occasioned by the flight of the projectile but instantly rendered ineffective at the initial impact of the projectile upon a target.

30. In a fuse, the combination of an impact firing pin, a detonator, a spacing member between the firing pin and the detonator, means energized by set back for advancing the detonator and, through the spacing member, for advancing the firing pin, and a connection between the firing pin and the spacing member including radially movable elements, whereby, upon impact of the pin with an object, relative movement of the pin with respect to the spacing member readily takes place to permit of impingement of the firing pin on the detonator.

31. In a fuse, the combination of a fuse body, a firing pin, a detonator, a spacing member between the firing pin and the detonator, means formed on the fuse body to engage said firing pin and positively limit the rearward movement of said pin, means energized by set back for advancing the detonator and, through the spacing member, for advancing the firing pin, and a connection between the firing pin and the spacing member including radially movable elements, whereby, upon impact of the pin with an object, relative movement of the pin with respect to the spacing member readily takes place to permit of impingement of the firing pin on the detonator.

32. In a fuse for a projectile, the combination of a fuse body, a firing mechanism adapted to move forwardly in said body from an inoperative position to active position during the flight of the projectile, an inertia member, and means cooperating with the latter member for normally preventing the forward movement of said mechanism and rendered ineffective upon discharge of the projectile from the gun.

33. In a fuse for a projectile, the combination of a fuse body, a firing pin, a detonator member, a spacing member interposed between the firing pin and the detonator member, so that forward movement of the latter will move the firing pin to its forward position through the medium of the spacing member, and means for normally preventing forward movement of the detonator member and 10 rendered ineffective upon discharge of the projectile from a gun.
34. In a fuse for projectiles, the combination of a striking member of the direct impact type and having a shoulder formed thereon, a detonator member, a safety member engaging one end of the detonator member and having spring tongue means to engage said shoulder, an inertia member, and a member having lateral projections cooperating with said inertia member to normally prevent the forward movement of the detonator member.
35. In a fuse for projectiles, the combination of a fuse body, a detonator member, a 25 firing pin member slidably mounted in said body, a member temporarily interposed between the firing pin and the detonator so that said three members may move in unison to active position, and means normally preventing said movement but rendered ineffective at the discharge of the projectile from a gun.
36. In a fuse for projectiles, the combination of a fuse body, a firing mechanism adapted to move forward integrally in said body from an inoperative position to an active position during the flight of the projectile and means adapted to be energized during the initial acceleration of the projectile to cause the movement of said mechanism to active 40 position.
37. In a fuse for projectiles, the combination of a fuse body, a firing mechanism, said firing mechanism comprising a movable firing pin and a movable detonator member, a spacing member interposed between said pin and said member whereby the forward movement of the detonator member causes a forward movement to the firing pin and means adapted to be energized upon shock of discharge of the projectile from a gun to cause the forward movement of the detonator member.
38. In a fuse for projectiles, the combination of a fuse body, a firing mechanism adapted to move forwardly in said body from an 55 inoperative position to an active position during the flight of the projectile, means normally preventing the forward movement of said firing mechanism but rendered ineffective during the discharge of the projectile from a gun, and means adapted to be energized during the initial acceleration of the projectile to cause the forward movement of the detonator member.
39. In a fuse for projectiles, the combination of a fuse body, a firing mechanism adapted to move forwardly in said body from an inoperative position to an active position during the flight of the projectile, means normally preventing the forward movement of said firing mechanism but rendered ineffective during the discharge of the projectile from a gun, and means adapted to be energized during the initial acceleration of the projectile to cause the forward movement of the detonator member.
40. In a fuse for projectiles, the combination of a fuse body, a firing mechanism, said mechanism comprising a movable firing pin and a movable detonator member, a spacing member interposed between said pin and said member whereby the forward movement of the detonator member causes a forward movement to the firing pin, means for normally preventing the movement of said detonator member but rendered ineffective during the discharge of the projectile from a gun, and means adapted to be energized during the initial acceleration of the projectile to cause the forward movement of the detonator member.
41. In a fuse for projectiles, the combination of a movable detonator member, a movable firing pin member, a safety member interposed between the firing pin member and the detonator member so that all of said members may move in unison from inoperative to active position, and means for effecting said movement.
42. A projectile fuse comprising striking and detonating members movable from inoperative to firing position, a safety member for separating the striking and detonating members, clutching means for connecting the safety member to one of the first-named members as long as the latter occupy inoperative positions and releasable when such members move forwardly to a predetermined extent, and means for moving said members forwardly.
43. In a fuse for projectiles, the combination of a movable detonator member, a movable firing pin, a safety member interposed between the firing pin and the detonator member so that they move in unison from inoperative to active position, means normally preventing the movement of said detonator member and the firing pin to active position adapted to be rendered ineffective prior to impact of the projectile against an object and means for moving the detonator member and the firing pin to active position after the first-mentioned means has been rendered ineffective.
44. In a fuse for projectiles, the combination of a movable detonator member, a movable striking member, a safety member interposed between the latter and the detonator member so that they move in unison from inoperative to active position, said safety member having releasable engagement with one of said other members, means for moving said striking member and detonator member

to active position and means to control said releasable engagement while said members are in their inoperative position.

45. In a fuse for a projectile, the combination of a fuse body, a firing pin adapted to protrude beyond said body, a detonator member, a spacing member interposed between the firing pin and the detonator member, so that forward movement of the latter will move 10 the firing pin to its forward position through the medium of the spacing member and means for normally preventing forward movement of the detonator member and rendered ineffective upon discharge of the 15 projectile from a gun.

46. In a fuse for projectiles, the combination of a fuse body, a detonator member, a firing pin slidably mounted in said body and adapted to protrude beyond said body, a 20 member temporarily interposed between the firing pin and the detonator so that they move in unison to active position and means normally preventing said movement but rendered ineffective at the discharge of the projectile 25 from a gun.

47. A fuse for projectiles, the combination with a fuse body having an open recess formed therein, of a detonator member slidably mounted in said recess, a striking member slidably mounted in said recess, a spacer interposed between said members and having portions thereof constituting a releasable means to engage with one of said members, one of said members adapted to move in said recess and through said spacer move the other member whereby the latter protrudes beyond the fuse body and said members are moved from inoperative to active position, means normally locking said releasable means rendered ineffective after said members have moved a predetermined extent, means normally preventing the movement of said members rendered ineffective prior to the projectile reaching its object and means activated after the last mentioned means has been rendered ineffective for moving said members forwardly.

In testimony whereof I hereunto affix my signature this 13th day of May, 1924.

PIETER DANIEL VAN ESSEN.
